UNITED STATES PATENT OFFICE.

JAMES H. MACBRIDE, OF TAFT, CALIFORNIA.

RAZOR-STROP.

1,244,754.

Specification of Letters Patent. Patented Oct. 30, 1917.

Application filed March 2, 1917. Serial No. 153,094.

To all whom it may concern:

Be it known that I, JAMES H. MACBRIDE, citizen of the United States, residing at Taft, in the county of Kern and State of California, have invented certain new and useful Improvements in Razor-Strops, of which the following is a specification, reference being had to the accompanying drawings.

10 This invention relates to razor strops, and particularly to certain details of construction of the strop whereby the stropping surface is cushioned and at the same time suitably supported to secure the stropping action and also to certain improved details whereby the end yokes at the ends of the strop may be readily connected thereto.

15 A further object of the invention is to provide a razor strop of this kind wherein the strop is adapted to be supported at one end and held by the hand of the user at the other end, but in which the middle portion of the strop is given a relatively firm support thus securing a better stropping action.

20 25 Other objects will appear in the course of the following description.

My invention is illustrated in the accompanying drawings, in which:—

Figure 1 is a plan view of a razor strop 30 constructed in accordance with my invention;

Fig. 2 is a plan view of the base, the paper layer 15 being partly broken away;

Fig. 3 is a plan view of the base portion of 35 the strop looking at the opposite face thereof;

Fig. 4 is a section on the line 4—4 of Fig. 2;

Fig. 5 is a sectional perspective view 40 through the completed strop;

Fig. 6 is a longitudinal section on the line 6—6 of Fig. 1; and

Fig. 7 is a fragmentary edge elevation of the completed strop.

45 Referring to these drawings, it will be seen that what may be termed the base of the strop consists of a wooden strip, of any desired length, and of suitable width for the strop, this strip being designated 10. This strip is made of relatively thin wood, such as pine. The ends of this wooden strip 10 are thinned down as at 11 and attached to these thinned down ends, in any suitable manner, as for instance by the tacks 12, are 50 the leather pieces 13 which have a width equal to the width of the strip 10 and of any

suitable length. Extending along the edges of the strip 10 is a binding 14 of paper, or other suitable fabric, this binding extending along the lateral edges of the base 10 and 60 along the lateral edges of the leather pieces 13. Glued, pasted, or otherwise attached to each face of the strip 10 is a longitudinally extending strip of paper 15, which preferably has a width equal to the distance between the inturned edges of the binding 14. These strips 15 are glued uniformly over their entire inner surfaces so as to lie flat 65 down upon the wooden base 10.

One face of the strop is to be provided 70 with a hone 15^a and the other face of the strop is provided with a plurality of felt cushioning strips 16 and 17 and a leather strip 18 of fine grained leather. In constructing the stropping face, the layer 17 of 75 felt is first pasted to the leather 18 and then, when dry, the edge of the felt is shaved to a feather edge, then the second strip of felt 16 is pasted over the first strip of felt and these two pieces of felt and the 80 strop, after being dried and firmly connected to each other, are in turn glued or pasted to the face of the base, that is, glued over the paper surface 15 and the inturned margin of the binding 14, in the manner 85 shown in Fig. 5. The cushioning strips 16, 17 and the leather strip 18 are slightly narrower than the width of the base of the strop.

After the several layers or thicknesses of 90 material are attached to each other, as before described, the yokes 19 are connected to the ends of the strop by the leather clips 20. Each clip is folded upon itself so as to embrace the end of the strop and is sewed to 95 the end of the strop by the stitching 21. It will be seen that the inner line of stitching 21 passes through the flexible leather ends 13 and not through the wooden base 10. This makes it an easy matter to stitch the 100 clips 20 on to the ends of the strop and thus connect the yokes 19 to the strop. One of these yokes 19 carries a handle 22 and the other a swivel 23. It will, of course, be seen from the drawing that the stitching 21 passes through the thickness of material 105 which forms the hone 15^a and also through the stropping layer 18 and the cushioning layers 16 and 17. The paper strips 15 have a two-fold purpose in that these layers of 110 paper help to form the cushion and, furthermore, save the binding leather. The

layer of paper 15, and the two layers of felt 16 and 17 form a perfect cushion for the stropping layer 18.

My improved strop provides for a cushioned but firm support of the stropping leather, and at the same time the strop has all the capabilities of a flexible strop. The clips holding the handle and the swivel yoke in place may be readily sewed on. A strop 10 constructed in accordance with my invention gives a firm support for the razor while being honed, but has sufficient flexibility to secure all the advantages of a purely flexible strop, it may be cheaply made, and is very 15 effective in practice.

Having thus described my invention, what I claim is:—

1. A strop of the character described, comprising a base formed of a wooden strip less in length than the total length of the strop, 20 leather pieces attached to the ends of said base piece and extending beyond it, a honing layer and a stropping layer operatively attached to opposite faces of the base, leather 25 clips embracing the leather pieces at the ends of the base piece and attached thereto by sewing, and yokes engaged by said clips.

2. A razor strop of the character described, comprising a longitudinally extending 30 relatively stiff base less in length than the full length of the strop and having its thickness reduced at its ends, leather pieces

attached to the reduced ends of the base piece and extending beyond it, leather clips each folded upon itself and embracing the 35 leather piece at the end of the base piece and sewed thereto, and yokes engaged by said clips.

3. In a strop of the character described, a relatively stiff longitudinally extending 40 base, leather strips attached to the base and extending beyond it at each end, strips of binding material extending over the side edges of the base and of said strips, strips of paper pasted upon opposite faces of the 45 base piece between said binding strips, strop cushioning layers superimposed upon each other and pasted to each other and to one face of the base, a stropping layer pasted to the face of the outer cushioning layer, leather 50 clips each folded upon itself and embracing the leather strips at the ends of the strop and sewed thereto, the inside row of stitching being disposed outward of the adjacent 55 end of said stiff base and passing through the leather pieces at the ends of the base, and handle and swiveled yokes engaged by said clips.

In testimony whereof I hereunto affix my signature in the presence of two witnesses. 60

JAMES H. MACBRIDE.
